CHECK STRAP CHECK

William H. Bahan, Greenville, S. C.

Application November 3, 1939, Serial No. 302,744

3 Claims. (CL 139—165)

This invention relates to a picker stick check for looms and more especially to a device which can be easily adjusted so as to vary the resistance offered by the check strap when the stick is forced thereagainst.

The present invention is particularly useful in connection with a strap which encircles the picker stick and which has the end thereof secured to a projection from the lay whereby the strap will serve as a check for the stick when the stick is travelling in either direction. The principle involved in causing straps of this type to act as a check in the directing of a portion of the strap in a path or channel formed by gripping members disposed on opposed sides thereof. This path is usually not parallel to the lines of force exerted upon the strap by the picker stick, thereby setting up a frictional resistance to the slippage of the strap and causing the impact of the stick to be gradually absorbed. When the angle of the strap relative to the line of force is increased, the resistance to the movement of the strap will increase in a corresponding manner. Heretofore, there have been problems of adjusting and keeping adjusted, the angle at which the strap is directed relative to the line of force or to the line of travel of the stick, because after much use the strap becomes worn and the resistance is reduced. Also much trouble is encountered in maintaining the strap gripping members in the position to which they have been adjusted.

It is, therefore, an object of this invention to provide a member for gripping opposed sides of the loom check strap, which member is readily and easily adjustable and which will remain in adjusted position despite the vibration and strain set up by the picker stick.

Some of the objects of the invention having been stated, other objects will appear as the description proceeds when taken in connection with the accompanying drawing, in which—

Figure 1 is an elevation of a portion of a lay of a loom showing my improved picker stick check associated therewith;

Figure 2 is a sectional plan view taken along the line 2—2 in Figure 1;

Figure 3 is an isometric view of the picker stick check mechanism showing the same apart from the loom and looking from the opposite side from that shown in Figure 1.

Referring more specifically to the drawing, the numeral 10 denotes the lay of a loom having a box front 11 mounted thereon which forms a part of a shuttle box into which shuttle 12 is adapted to be received and from which it is adapted to be

expelled by means of a suitable picker 14 on the upper end of a picker stick 15. This picker stick moves back and forth from right to left in Figure 1, in a well known manner during the reception and the expulsion of the shuttle. The lay 10 has a downwardly projecting member 16 to which the ends of a check strap 17 are secured by any suitable means such as a bolt 18. By referring to Figure 2 it is seen that this bolt not only penetrates the member 16, but also penetrates slots 19, 20 and 21 which are cut in the ends of the strap 17 and in a suitable metallic plate 22.

The structure thus far described is conventional in looms. When the shuttle 12 is hurled into the shuttle box it strikes the picker 14, the picker stick 15 will be moved to the left. In order to check the impact or momentum of this stick, it is necessary to provide means for holding the strap 17 in such a manner that it will gradually give way under the impact of the picker stick. A similar restraining operation must be employed to check the stick 15 when it moves to expel the shuttle from the shuttle box. In order to provide a gripping means to produce this result, a suitable bracket 25 has been secured to the lower side of the lay 10 by any suitable means such as bolts 26 and 28. Extending downwardly from the member 25 is a projection 29, said projection having a laterally projecting lip 30 integral therewith, which projection supports the strap 17 approximately midway of its oval-shaped position. The member 25 also has a lug 31 extending laterally therefrom which is penetrated by a vertically disposed bolt 32. This bolt also penetrates a boss 33 which is in off-center position relative to a cam or pipe member 34. Since the head of the bolt 32 is disposed on the lower side of the member 34 and a lock washer 35, and a nut 36 is secured on the upper end of the bolt above the projection 31, the pipe member 34 will be held in adjusted position despite any movement of the strap 17. Figure 2 also shows the gripping action that produces the friction or resistance offered by the strap 17 to the picker stick 15. This resistance, as heretofore stated, is produced by bending a portion of the check strap which is disposed between the members 34 and 29 at an angle to the line of force exerted by the picker stick. Of course, the greater the angle that the strap makes at the gripping point, the greater the resistance which will be offered. This variation of the angularity can be effected by merely loosening the nut 36 and then turning pipe 34 to the desired position. The bracket 36 has a slot 36a therein which will permit the

35

55

55

bracket 25 to be adjusted to different positions on the bottom of the lay of the loom. This slot is penetrated by bolt 28 which has been previously described.

5 In the drawing and specification there has been set forth a preferred embodiment of the invention, and although specific terms are employed, they are used in a generic and descriptive sense only, and not for purposes of limitation, the scope of 10 the invention being set forth in the appended claims.

I claim:

1. In a loom having a lay provided with a shuttle box and a picker stick mounted for oscillatory movement in the shuttle box, and having a check strap surrounding the path travelled by the picker stick and having its ends secured together and anchored to the lay at one side of the path travelled by the picker stick, retarding 20 means disposed on the opposite side of the shuttle box from the anchoring member for engaging the check strap and retarding movement of the same under the force applied to the picker stick after receiving a shuttle and after discharging a shuttle, said retarding means comprising a bracket 25 secured to one side of the lay and projecting beneath the lay and having a downwardly extending leg provided with an out-turned projection for supporting the check strap, a cylindrical member disposed in vertical parallel relation to the leg, means on the bracket for eccentrically supporting said cylindrical member within the arcuate confines for adjustment, the cylindrical member being disposed in longitudinal off-set 30 relation to the leg and being adapted to engage 35 the other side of the check strap from that engaged by the leg to thereby provide a circuitous

course to be travelled by the check strap to thereby retard movement of the check strap in both directions longitudinally of the lay under the impact of the picker stick in its movement in receiving and expelling the shuttle. 5

2. Means for supporting and retarding one side of a picker stick check strap in the shuttle box of a loom, comprising a bracket secured to the lay and projecting beneath the lay, said bracket having a vertically disposed leg for engaging the 10 inner surface of the check strap, a cylindrical member adjustably and eccentrically mounted on the bracket and extending downwardly for engaging the outside of the check strap, the cylindrical member being disposed longitudinally of 15 the check strap relative to the leg, whereby the engaged portion of the check strap will be compelled to travel at an acute angle to the path of the picker stick when it is moved by impacts therefrom to thereby retard the picker stick at 20 points adjacent the end of its travel in both directions.

3. A bracket adapted to be mounted on a loom lay for engaging a picker stick check strap, said bracket having a vertically disposed member for 25 engaging one face of the strap, a vertically disposed cylindrical member for engaging the other face of said strap, said cylindrical member being adjustably and eccentrically mounted whereby a horizontal straight line drawn tangent to the 30 proximate faces of both members will be disposed at an acute angle to the longitudinal axis of the lay and whereby the cylindrical member can be rotated about its eccentric axis to vary the angularity of the engaged portion of the 35 check strap.

WILLIAM H. BAHAN.
